US00D918263S

(12) **United States Design Patent** (10) **Patent No.:** **US D918,263 S**
(45) **Date of Patent:** **** May 4, 2021**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Dennis Park**, San Francisco, CA (US);
Christopher Daryl Soli, Mountain
View, CA (US); **Christopher Wilson**,
San Francisco, CA (US)

(73) Assignee: **Apple Inc.**, Cupertino, CA (US)

(**) Term: **15 Years**

(21) Appl. No.: **29/756,735**

(22) Filed: **Oct. 30, 2020**

Related U.S. Application Data

(63) Continuation of application No. 29/734,231, filed on May 11, 2020, now Pat. No. Des. 910,689, which is a continuation of application No. 29/712,377, filed on Nov. 7, 2019, now Pat. No. Des. 884,730, which is a continuation of application No. 29/686,832, filed on Apr. 8, 2019, now abandoned, which is a continuation of application No. 29/629,977, filed on Dec. 18, 2017, now Pat. No. Des. 845,325, which is a continuation of application No. 29/604,021, filed on May 15, 2017, now Pat. No. Des. 805,556, which is a continuation of

(57) **CLAIM**

The ornamental design for a display screen or portion thereof with graphical user interface, as shown and described.

DESCRIPTION

The FIGURE is a front view of a display screen or portion thereof with graphical user interface showing the claimed design.

The broken lines in the FIGURE show a display screen or portion thereof, and form no part of the claimed design.

1 Claim, 1 Drawing Sheet

Related U.S. Application Data

application No. 29/540,552, filed on Sep. 25, 2015, now Pat. No. Des. 786,921, which is a continuation of application No. 29/492,617, filed on Jun. 1, 2014, now Pat. No. Des. 798,900.
